OF D 905

No 905.

Design for a Cottage Parlor Stove,
By John C. Smith, of Troy, N. Y.,
Assignor to Messrs. W. Risor & Co. of Cincinnati, Ohio.

Patented July 7. 1857.

Pat. 905

John L. Smith, of Troy, N. Y.
Assignor to
W. Resor & Co. of Cincinnati, O.
Letters Patent No. 905, Dated July 7th 1857.

The schedule referred to in these Letters Patent, and making part of the same

To all whom it may concern:

Be it known that I, John L. Smith, of the City of Troy, in the County of Rensselaer, and State of New York, have invented or produced a new and original design for a Parlor Stove called the "Basket", and I do hereby declare that the following is a full and exact description of the same, - reference being had to the annexed photographic drawing, making a part of this specification. -

2

Dec. 905

My ornamental design for a parlor stove consists of the compound ornaments, A, upon the top part, and the ornaments, B, B', upon the sides of the front plate of the upper section of the stove; the compound ornaments C, C', upon the doors of the upper front plate; the ornamental border D, of the top-plate of the lower section of the stove; the compound ornaments E, E', upon the sides of the front plate of the lower section of the stove; and the compound ornaments G, G', upon the doors of the lower front plate.

What I claim as my invention or production and desire to secure by letters patent, is the ornamental design, herein specified and fully shown in the annexed photographic drawing, for the upper and the lower front plates, with their respective doors, and the top-plate of the lower section, of a parlor stove.
